COMBINED STAND AND DISPENSER FOR POWDERED MATERIAL

David V. Parker, Pacific Palisades, Calif., assignor to
United States Borax & Chemical Corporation, Los Angeles, Calif., a corporation of Nevada

Filed Aug. 1, 1961, Ser. No. 66,234

Term of patent 14 years

(Cl. D4—3)

FIG. 1 is a side elevational view of a combined stand and dispenser for powdered material showing my new design, the opposite side being substantially the same in appearance as indicated in FIG. 5;

FIG. 2 is a front elevation;

FIG. 3 is a top plan view;

FIG. 4 is a side elevational view showing the stand element in reverse position; and

FIG. 5 is a top perspective view taken from the right of FIG. 1 and on a reduced scale.

I claim:

The ornamental design for a combined stand and dispenser for powdered material, as shown and described.
